[57] CLAIM

The ornamental design for a combined bed and control

unit for an industrial oxygen concentrator, or the like as shown and described.

DESCRIPTION

FIG. 1 is a top front perspective view of a combined bed and control unit for an industrial oxygen concentrator, showing my new design;

FIG. 2 is a front elevation thereof;

FIG. 3 is a rear elevation thereof;

FIG. 4 is a side elevation thereof;

FIG. 5 is an elevation of the side opposite FIG. 4;

FIG. 6 is a top plan view thereof;

FIG. 7 is a top front perspective view of a second modified embodiment of the combined bed and control unit illustrated in FIG. 1;

FIG. 8 is a front elevation thereof;

FIG. 9 is a rear elevation thereof;

FIG. 10 is a side elevation thereof;

FIG. 11 is an elevation of the opposite side of FIG. 10;

FIG. 12 is a top plan view thereof;

FIG. 13 is a top front perspective view of a third modified embodiment of the combined bed and control unit illustrated in FIG. 1;

FIG. 14 is a front elevation thereof;

FIG. 15 is a rear elevation thereof;

FIG. 16 is a side elevation thereof;

FIG. 17 is an elevation as seen from the side opposite FIG. 16; and

FIG. 18 is a top plan view thereof.

FIG. 1.

FIG. 2.

FIG. 3.

FIG. 4.

FIG. 5.

FIG. 6.

FIG. 7.

FIG. 8.

FIG. 9.

FIG. 10.

FIG. 11.

FIG. 12.

FIG. 13.

FIG. 14.

FIG. 15.

FIG. 16.

FIG. 17.

FIG. 18.
